UNITED STATES PATENT OFFICE

159,726

FORCE CUP

Fred Emanuel Grosvold, Eau Claire, Wis.

Application August 23, 1949, Serial No. 4,655

Term of patent 14 years

(Cl. D9—2)

To all whom it may concern:

Be it known that I, Fred Emanuel Grosvold, a citizen of the United States, residing at Eau Claire, county of Eau Claire, and State of Wisconsin, have invented a new, original, and ornamental Design for a Force Cup, of which the following is a specification, reference being had to the accompanying drawing forming a part hereof.

Fig. 1 is a side view of a force cup showing my new design;

Fig. 2 is a vertical sectional view taken on the line 2—2 of Fig. 1; and

Fig. 3 is a bottom view.

I claim:

The ornamental design for a force cup, as shown.

FRED EMANUEL GROSVOLD.
